UNITED STATES PATENT OFFICE

ROSCOE G. BICKNELL, OF WORCESTER, MASSACHUSETTS

LOCKING DEVICE FOR CLOTHES DRIERS

Application filed January 27, 1932. Serial No. 589,264.

This invention relates to a locking device for clothes driers, the general object of the invention being to provide means for preventing the reel from being removed from the post while the same is in spread position and for preventing the wind from blowing the reel with the clothes thereon from the upright.

This invention also consists in certain other 10 features of construction and in the combination and arrangement of the several parts to be hereinafter fully described, illustrated in the accompanying drawings and specifically pointed out in the appended claims.

15 In describing the invention in detail, reference will be had to the accompanying drawing wherein like characters denote like or corresponding parts throughout the several views, and in which:

20 Figure 1 is an elevation of the upper part of the improved drier.

Fig. 2 is a vertical sectional view through a portion thereof.

Fig. 3 is a plan view.

25 In the drawing, the numeral 1 indicates the upright and the numeral 2 indicates the hub of the reel which is formed with the outwardly and downwardly extending pairs of ears 3, each pair of which receives the inner end of an arm 4 to which the arm is pivoted as at 5, these arms having holes therein for receiving the cords or flexible members 6 as is usual. The links 7 for pivotally connecting the arms to the upper end of the hub 30 are pivoted to the ears 8 on the upper end of the hub.

The upper end of the upright is formed with an inverted frusto-conical part 9 for receiving the beveled parts 10 at the inner ends 40 of the arm 4 so that these beveled parts and the member 9 act to lock the reel to the upright when the arms are in extended position as shown in Fig. 1 and in full lines in Fig. 2, but when the arms are swung upwardly as shown in dotted lines in Fig. 2 the

reel can be removed from the upright. This arrangement prevents the reel from being blown off the upright by the wind acting on the clothes on the flexible members for even though one of the arms, or a number of the 50 arms are partly swung upwardly by the wind, the locking device will still act to hold the reel on the upright, for the arms would have to be moved to a vertical position before the reel could be lifted from the upright and this 55 is particularly practically impossible unless the arms are lifted by hand.

As will be seen the inner ends of the arms 4 are of ridge shape, so that the inner ends have considerable strength and there are no parts likely to be broken off from rough usage, and the conical part 9 engages the beveled inner end of the arm to the entire length of the bevel and along its straight edge so that the engagement of the arm with the member 9 is a firm one and thus the reel is firmly locked to the upright and cannot be removed therefrom until the arms are swung to vertical position. The bevels 10 only engage the cone 9 when the hub is moved upwardly as the bevels are spaced from the cone when the reel is in normal position.

It is thought from the foregoing description that the advantages and novel features of the invention will be readily apparent.

It is to be understood that changes may be made in the construction and in the combination and arrangement of the several parts provided that such changes fall within the 75 scope of the appended claims.

Having thus described my invention, what I claim as new is:

1. In combination with an upright having an inverted substantially conical part adjacent its upper end, a hub fitting over the upper end of the upright and having arms pivotally connected thereto, each arm having a beveled inner end for engaging the substantially conical member, when the arms are in 80 85 90

lowered position for locking the hub to the upright.

2. In a clothes drier of the class described, an upright, a reel supported thereby and including a number of arms and a hub to which the arms are pivoted, a substantially inverted frusto-conical member on the upright under the hub and the inner end of the arms being wedge-shaped with their upper bevels contacting the frusto-conical member to lock the reel to the upright when the arms are in lowered position, and the reel is moved upwardly from its normal position.

In testimony whereof I affix my signature.

ROSCOE G. BICKNELL.
